[57] CLAIM

The ornamental design for an arm swim fin, as shown and described.

DESCRIPTION

FIG. 1 is a perspective view of an arm swim fin, showing my new design;

FIG. 2 is a top-plan view thereof;

FIG. 3 is a bottom-plan view thereof;

FIG. 4 is a rear elevational view thereof, the front elevational view being a mirror image of that shown; and
FIG. 5 is a side-elevational view thereof.

FIG. 1

FIG. 2

FIG. 3

FIG. 4

FIG. 5
